UNITED STATES PATENT OFFICE.

PHILIP HERBOLD, OF GALION, OHIO.

CONVERTIBLE BED AND SEAT.

1,033,013.

Specification of Letters Patent. Patented July 16, 1912.

Application filed March 23, 1912. Serial No. 685,888.

To all whom it may concern:

Be it known that I, PHILIP HERBOLD, citizen of the United States, residing at Galion, in the county of Crawford and State 5 of Ohio, have invented certain new and useful Improvements in Convertible Beds and Seats, of which the following is a specification.

This invention relates to convertible beds 10 and seats, and is an improvement on the article shown in my application, Serial No. 649931.

The object of the present invention is to provide improved means for converting the 15 article from a bed to a seat, or vice versa, so that it may be more readily and easily changed from one to the other.

A further object of the invention is to provide an improved stop or support to 20 assist in holding the parts in position when adjusted to form a seat.

In the accompanying drawings—Figure 1 is a perspective view of the article in partly 25 converted position, as in changing from bed to seat, or vice versa. Fig. 2 is a side elevation of the device when folded to form a seat. Fig. 3 is a side elevation of the article adjusted to form a bed.

The main parts of the article are similar 30 to those described in my above entitled application. That is, 6 indicate the main legs braced by bars 6^a and upper bars 24 at the ends. The back frame 8 swings up and down on pivots 7 at the top of the rear legs, 35 and the end pieces of said back frame have lugs 25 which stop against the end bars 24 when the back is swung down to form the bed, to prevent upward tilting of back frame 8 at hinged point. The seat 40 frame has side pieces 21 and a front piece 21^a, and legs 16 at the front, and the rear ends of the side bars 21 are connected to the lower ends of the side pieces of the back frame 8 by means of links 12, the links being 45 hinged as at 27 to the seat and back frames respectively. 30 is a cross bar extending between the rear ends of the pieces 21 for the purpose of making the back part of the seat frame rigid, so that it cannot spread 50 or be drawn together by the strain of the spring fabric or the like with which the frames will be covered. This fabric is omitted from the drawings, for the sake of clearness since the invention relates to the 55 frame structures which may be covered with any material desired and provided with suit-

able pads or upholstery. The above described parts are substantially the same as those disclosed in my application above referred to.

A new feature of the present invention is the use of links 22 which are pivoted to the side pieces 21 on the seat frame, as indicated at 22^a, and also to the front ends of the side bars 24, as indicated at 22^b. These links 22 60 guide or control the movement of the seat frame, as it is shifted in or out to form either a seat or a couch or a bed. When the parts are adjusted to form a seat as in Fig. 2 the side bars 21 of the seat frame fit in 65 between the side bars 24 of the fixed or main frame, and the inner ends of said bars 21 are then supported on inwardly projecting flanges or brackets 26 attached to the bars 24, the links 22 folding down between the 70 bars 21 and 24. When the device is to be converted into a bed, the seat frame is pulled upwardly and forwardly, and swings over on the links 22 to the extended position 75 shown in Fig. 3, and by the same action the back 8 is swung down and the links 12 are 80 swung up and out or unfolded, to rest on the lugs 26, whereby the back 8, the links 12, and the seat frame 21 are all in the same plane, suitable to support and form a bed 85 bottom. The links 22 serve to hold the seat frame in position and to enable it to be more easily operated than if they were omitted.

As a further improvement I provide the 90 rear ends of the bars 21 with downwardly projecting stops 23 which depend in such position that when the device is adjusted to form a seat, as shown in Fig. 2, the links 12 will abut against said pieces 23. This prevents any further swing of said links and 95 assists in holding the back in position, rigidly, preventing any looseness or tendency of the parts to yield or buckle under the effect of pressure on the back, and when in the position shown in Fig. 2 the lugs 25 100 stop against the rear legs 6, as shown in said figure, whereby the lower end of the back is, so to speak, confined between the stops 23 and the rear legs 6, which serves to prevent any looseness or movement of the 105 back under pressure.

What I claim as new is:

1. In a convertible bed and seat, the combination of a fixed frame, a back frame pivoted to the fixed frame to swing to horizontal or upright position, a seat frame, swinging links connecting the sides of the seat 110

frame, and the fixed frame, and permitting the seat frame to be shifted in or out at the front of the fixed frame, and pivoted links connecting the lower end of the back frame 5 and the seat frame.

- 10 2. In a convertible bed and seat, the combination of a fixed frame, a back frame pivoted thereto to swing to horizontal or upright position, a seat frame shiftable in or out at the front of the fixed frame, pivoted links connecting the rear end of the seat frame and the lower end of the back frame, and stops projecting from the seat frame and arranged to be struck by, and limit the 15 swing of, said links, when the seat frame is shifted in and the back frame is swung to upright position.
- 15 3. In a convertible bed and seat, the com-

20 bination of a fixed frame, a back frame pivoted to the rear part of the fixed frame and adapted to swing to either upright or horizontal position; a seat frame, swinging links connecting the opposite sides of the seat frame and the sides of the fixed frame, links connecting the rear end of the seat frame 25 and the lower end of the back frame, and stops projecting from the seat frame and arranged to be struck by the last mentioned links when the back frame is swung to upright position.

25 30 In testimony whereof, I do affix my signature in presence of two witnesses.

PHILIP HERBOLD.
